UNITED STATES PATENT OFFICE

2,691,404

BATHTUB SEAT UNIT

Harry Baird Saunders, Woodland, Calif.

Application December 23, 1952, Serial No. 327,565

6 Claims. (Cl. 155—36.5)

1

This invention is directed to, and it is a major object to provide, a bathtub seat unit of novel structure; the unit being especially designed—but not limited—for use to support invalid or aged persons in a bathtub for the purpose of bathing.

Another important object of the present invention is to provide a bathtub seat unit which is arranged for vertical adjustment of the seat between a raised position adjacent the top of the tub to aid a person to gain access to the seat, or to leave the same; and a lowered position in the tub for bathing.

An additional object of the invention is to provide a bathtub seat unit which includes a power device, in novel combination in the structure, to raise—and to control lowering of—the seat; such power device being a hydraulic jack having operating and control members positioned for ready manipulation by the person occupying the seat.

A further object of the invention is to provide a bathtub seat unit which includes a novel supporting structure for the assembly of the hydraulic jack and seat carried thereby; such supporting structure embodying a base which rests on the bottom of the bathtub, and anti-displacement hangers engaging over the outer side of said bathtub.

A still further object of the invention is to provide a bathtub seat unit which is arranged so that the hydraulic jack and seat assembly are normally fixed on the supporting structure, but may be detached for the purpose of cleaning, repair, or storage of said jack and seat assembly. Also, with the supporting structure, and the jack and seat assembly initially separate, installation of the unit in a bathtub is facilitated.

It is also an object of the invention to provide a bathtub seat unit which is designed for ease and economy of manufacture.

Still another object of the invention is to provide a practical and reliable bathtub seat unit, and one which will be exceedingly effective for the purpose for which it is designed.

These objects are accomplished by means of such structure and relative arrangement of parts as will fully appear by a perusal of the following specification and claims.

In the drawings:

Fig. 1 is a side elevation of the bathtub seat unit as in use in a bathtub; the latter being in section.

Fig. 2 is an enlarged plan view of the unit.

Fig. 3 is a transverse section on line 3—3 of Fig. 2.

Referring now more particularly to the charac-

2

ters of reference on the drawings, the improved bathtub seat unit comprises a rectangular base plate 1 provided on the bottom with a resilient non-slip pad 2, preferably of rubber or the like.

5 A pair of transversely spaced hangers, each indicated at 3, upstand from one side of the base plate 1; each hanger including vertical upper and lower straps, indicated at 4 and 5. Lapped end portions of straps 4 and 5, of each hanger 3, are secured in vertically adjustable relation by a pair of vertically spaced screws 6 having manipulating heads 7 thereon; such heads being of rubber, whereby to prevent injury should a person bump against the same.

15 The vertical adjustment between the upper and lower straps is accomplished by providing rows of holes (not shown) in such straps adapted to match in different positions of adjustment, with the holes in the upper strap 4 being tapped for threading engagement with the screws 6.

At the upper end thereof each hanger 3 includes a hook 8 adapted to engage over the rim 9 on the adjacent side of a bathtub 10; the vertical adjustment of the length of the hangers, as previously described, being for the purpose of setting the hooks 8 in proper engagement with the rim 9 when the base plate 1 and its pad 2 rest on the bottom 11 of the tub.

Each of the upper straps 4 and the related hook 30 8 have a resilient anti-displacement lining 12 for tub engagement.

With this structural arrangement the base plate 1 can be disposed on the bottom 11 of the bathtub 10 in a stabilized position.

35 A hydraulic jack unit 13 is disposed substantially centrally on the base plate 1, and includes a rectangular supporting plate 14, being normally maintained in position by the following:

The base plate 1 is formed, on top thereof, with 40 a pair of transversely spaced, laterally inwardly opening channels 15 disposed in parallelism; the spacing of the channels 15 being such that the supporting plate 14 may slide thereinto from the front of the device. The supporting plate 14 is 45 prevented from sliding rearwardly out of the channels 15 by a back-stop 16 which upstands from the base plate 1.

The supporting plate 14 is normally prevented from sliding forwardly out of the channels 15 by a 50 cross slide 17 carried in a guide 18 atop said base plate 1 at the front of, but somewhat laterally disposed from, the supporting plate 14.

At its outer end—i. e. laterally out from the guide 18—the cross slide 17 includes an upstanding finger grip 19. When the cross slide 17 is 55 advanced inwardly its inner end projects beyond

the adjacent channel 15 and laps the adjacent corner of the supporting plate 14, as at 20, thus effectively blocking said supporting plate against accidental forward sliding from said channels 15.

The hydraulic jack unit 13, which is of substantially the same structure as hydraulic jacks used for automotive service, includes a telescopic post 21. A pump 22, when worked by a pump actuating handle 23 to one side of the vertical axis of the jack unit 13, causes the telescopic post 21 to rise or extend in the manner shown in dotted lines in Fig. 1. The pump actuating handle 23 includes a knob on its outer end, as at 24, for ease of grasping. Additionally, the hydraulic jack unit 13 includes a pressure release valve 25 worked by a turnable rod 26 having a finger tab 27 on its upper end; the rod 26 extending adjacent the handle 23. By simply turning the rod 26, the pressure release valve 25 may be opened, whereby to permit the telescopic post 21 to slowly contract or lessen in its vertical extent.

At its upper end the telescopic post 21 is fitted with a conforming seat 28, and at the rear of such seat a spring arm 29 extends upwardly on a gradual curve; such arm being fixed at its lower end to the upper end of the post 21. At its upper end the spring arm 29 supports a back rest 30 in vertically adjustable relation. Such adjustment of the back rest 30 is accomplished by providing the same with a guide yoke 31 through which the spring arm 29 is slideable, but the sliding is normally prevented by a set screw 32 threaded through the yoke 31, and having a rubber head 33 on its outer end.

After the described bathtub seat unit is disposed in a bathtub 10 in the manner described, the hydraulic jack unit 13 is worked by the pump actuating handle 23 to cause the telescopic post 21 to extend, raising the seat 30 to approximately the horizontal plane of the rim 9 of the bathtub.

With the seat in such raised position, an invalid, or an aged person, can gain access to such seat without difficulty or danger of falling.

Thereafter, the rod 26 is rotated in a direction to cause release of the valve 25, whereupon the telescopic post 21 gradually retracts, lowering the seat 28 and the occupant into the bathtub 10. In the lowered position of the seat 28, bathing can be accomplished with relative ease, yet with adequate support of the person occupying said seat 28.

When the bathing is completed, the hydraulic jack unit 13 is again worked to cause the telescopic post 21 to extend, raising the seat back to its starting point, and from which the occupant can readily leave the bathtub.

As the handle 23 and rod 26 are disposed to one side of the device, and laterally of the seat 28, such handle and rod can be easily reached and manipulated by the occupant of the bathtub seat unit; this being a feature further assuring of convenience and safety of use.

As an aid to initial installation of the device in a bathtub, or the removal of the hydraulic jack and seat assembly for cleaning, repair or storage, the supporting plate 14 can be detached from the remainder of the structure by retracting the cross slide 17 and thence sliding the plate 14 forwardly until it escapes the guide channels 15.

From the foregoing description it will be readily seen that there has been produced such a device as substantially fulfills the objects of the invention, as set forth herein.

While this specification sets forth in detail the present and preferred construction of the device, still in practice such deviations from such detail

may be resorted to as do not form a departure from the spirit of the invention, as defined by the appended claims.

Having thus described the invention, the following is claimed as new and useful, and upon which Letters Patent are desired:

1. A bathtub seat unit comprising a supporting structure adapted to rest on the bottom of a bathtub, said structure including an upstanding hanger having a hook for engagement over the rim of the bathtub on one side, a jack mounted on and upstanding from the supporting structure, the jack including operating means arranged to raise the same and control its lowering, and a seat mounted on the upper end of the jack.

2. A bathtub seat unit, as in claim 1, in which the hanger is vertically adjustable.

3. A bathtub seat unit, comprising a base plate adapted to rest on the bottom of a bathtub, spaced hangers upstanding from one side of the base plate, said hangers being vertically adjustable and having upper end hooks for engagement over the rim of the bathtub on one side, a hydraulic jack upstanding from the base plate, said jack including a supporting plate resting on the base plate, a telescopic post, a pump handle and a valve release member; means securing the supporting plate on the base plate, and a seat mounted on the upper end of the telescopic post.

4. A bathtub seat unit, comprising a base plate adapted to rest on the bottom of a bathtub, spaced hangers upstanding from one side of the base plate, said hangers being vertically adjustable and having upper end hooks for engagement over the rim of the bathtub on one side, a hydraulic jack upstanding from the base plate, said jack including a supporting plate resting on the base plate, a telescopic post, a pump handle and a valve release member; transversely spaced parallel channels on the base plate opening toward each other, the supporting plate resting on the base plate and slidably engaged at opposite edge portions in said channels, releasable means preventing escape of the supporting plate from the channels, and a seat mounted on the upper end of the telescopic post.

5. A bathtub seat unit, as in claim 4, in which said releasable means includes a cross slide mounted on the base plate for sliding between a position in front of one end of the supporting plate, and a position clear thereof; there being a stop beyond the other end of said supporting plate.

6. A bathtub seat unit comprising a supporting base unit adapted to be supported on the bottom of a bathtub, a jack mounted on the base unit and disposed entirely above the same whereby the base unit may rest flatly over substantially its entire area on the bottom of the tub, a seat above the base unit, means between the seat and jack to raise and lower the seat upon operation of the jack, and means on the base unit to releasably engage the rim of the bathtub to maintain the base unit in place in the bathtub.
